[57] ABST

A sample cartridge is provided with interior lip and is adapted to receive a predetermined quantity of sample material and closure means therein. The lip being effective to grippingly engage the closure means so as to establish a fluid pressure seal therewith and prevent expansion or elastic return of the sample material contained in the cartridge. Additionally, a machine is disclosed for metering the sample material and closure means to the cartridge so as to obtain uniform density or packing of the material in the cartridge. A rotatable valve is provided for receiving the sample material and thereafter is movable to a position in alignment with a packing ram which moves the sample material and closure means to a position effecting the packing of the material in the cartridge and securing the closure means in gripping engagement with the lip of the cartridge.

SAMPLE CARTRIDGE FILLING AND CLOSING APPARATUS

BACKGROUND OF THE INVENTION

This invention is primarily concerned with the packing of samples for testing wherein it is necessary that the volume or bulk density of the material being sampled is maintained uniform. By bulk density, it is meant that a given weight of material will be confined within a given volume. This is particularly significant wherein small samples are to be utilized and the analysis procedures are particularly sensitive such as in neutron activation analysis. Prior attempts to package samples have required that the sample material be hand-packed into cartridges and thereafter the cartridges are closed by means of a screw cap. This was undesirable and disadvantageous since that hand-packing resulted in various degrees of pressure being exerted on the material such that uniform bulk densities were not obtained. The effect of non-uniform pressure being exerted on the sample material is that the sample material could be overly compressed and air pockets or spaces produced in the sample cartridge. Since the material would not be consistently packed within a given volume, erroneous or poor readings in the analysis of the material could result. In addition, if the hand-packing operations were not performed with sufficient pressure, there was a great probability that the elasticity of the material being tested would be sufficient for it to expand above the top of the sample cartridge following packing so that the placement of the screw cap on the cartridge was difficult and could result in the loss of a portion of the material being tested. This loss of material would also result in erroneous or poor results.

In addition, these prior attempts to provide the sample material in cartridges have required a great degree of handling so that a substantial amount of time was required in the packing of each of the samples.

SUMMARY OF THE INVENTION

It is, therefore, the principal object of the present invention to provide a means of sealing samples in a cartridge whereby a given weight of material is confined within a given volume so that the bulk density of the sample materials will be substantially uniform.

Another object of the present invention is to provide an apparatus for automatically loading and closing the capsule device.

Another object of the present invention is to provide an apparatus for automatically feeding the sample material and closure means to the capsule with a predetermined pressure so as to insure that the sample materials will be packed into a given volume and the bulk densities of the samples are maintained substantially uniform.

It is another object of the present invention to provide a cartridge device having closure means which is automatically fitted into place and wherein the apparatus utilized for loading the cartridge device insures the proper placement of the closure means in the cartridge device.

Briefly, one aspect of the present invention comprises a sample cartridge having inwardly extending lip means in the opening thereof and closure means adapted for insertion into the cartridge, said closure

means being adapted for gripping engagement with said lip means to provide a pressure fluid seal therewith. Another aspect of the present invention is an apparatus for filling said cartridge which comprises a rotary valve adapted to receive a predetermined quantity of the sample material and adapted to be rotated to a position in alignment with the cartridge and the closure means, and a packing ram moveable to a position positioning said closure means and sample in the cartridge.

These and other objects and advantages of the present invention will become apparent by referring to the appended specification.

BRIEF DESCRIPTION OF THE DRAWINGS

In the accompanying drawings which form a part of this specification and wherein like numerals refer to like parts wherever they occur:

FIG. 1 is a cross-sectional view of the capsule device embodying the present invention and having a closure means positioned therein,

FIG. 2 is an enlarged cross-sectional view of the closure device of FIG. 1,

FIG. 3 is a side view of the apparatus of the present invention having a portion thereof broken away,

FIG. 4 is a top view of the apparatus of FIG. 3, and

FIG. 5 is a sectional view taken along the line 5-5 of FIG. 4.

DESCRIPTION OF THE PREFERRED EMBODIMENTS

Referring now to FIGS. 1 and 2, the sample cartridge or capsule device indicated generally at 1 consists of a cylindrical capsule portion 2 for receiving the material to be sampled and a closure device or lid 3. The cartridge 2 has an opening 4 therein with an annular inwardly extending lip or bead 5 which is substantially in a triangular shape. The shape of the capsule 2 may be of any configuration and the configuration illustrated in FIG. 1 is merely one example of the type of capsule or cartridge which may be utilized for conveying samples through pneumatic tubes. The closure device or cap 3 is provided with a groove 6 and an angular flanged lower portion 7. The groove 6 is sized such that when the closure device 3 is placed in the capsule 2, the lip means 5 and particularly the opposed sides of the triangular bead are grippingly engaged by the opposed sides of the groove 6 and a pressure fluid seal is established between the closure device 3 and the capsule 2. In addition, it should be noted that the angles flange portion 7 is adapted for readily being received within the capsule 2 and easily passes over the upper tapering portion 55 of the triangular bead of the lip 5 for insertion and thereafter the flange 7 and the lower tapering portion of the triangular bead of the lip 5 prevents removal of the closure device 3 from the capsule 2. Thus, the flange member 7 serves to insure that the gripping engagement between the lip means 5 and groove 6 are maintained.

It should be noted that the cavity 8 formed in the capsule 2 when the closure device 3 is positioned forms a core for the sample material having a selected volume and when the cavity 8 is completely filled by a given weight of material, the bulk density of the material contained therein will be substantially uniform.

Referring now to FIGS. 3 and 4, the sample packing apparatus, generally indicated at 10, is shown for automatically packing a predetermined amount of sample material and the closure device 3 into the capsule or cartridge 2. The automatic packing apparatus 10 is provided with a base 11 having connected thereto a standard commercially available air cylinder 12. The air cylinder 12 is provided with a push rod 13 connected in a standard manner. The air cylinder 12 is of the positive air actuation type such that the piston contained therein is responsive to air pressure applied thereto for moving the push rod 13 in a forward and reverse direction. The selection of the size of the air cylinder 12 is determined by the magnitude of force which it is desirable to produce by the push rod 13.

A sample loading and control means indicated generally at 14 is connected to the base 11 by suitable means such as bolts, at a position adjacent to the outwardly extending end of the push rod 13 when it is in its inoperative position. The control device 14 includes a mounting block or housing 15 having a large opening 16 therein which is connected to a smaller opening 17 and the openings 16 and 17 extend through the mounting block 15 as best seen in FIG. 4. An opening 18 is provided through the block member 15 and intersects the opening 16. The opening 18 is provided in axial alignment with the push rod 13 and is such that a very close tolerance is maintained between the walls thereof and the push rod when the push rod passes therethrough. In addition, the mounting block 15 contains a sample material inlet 19 which is provided centrally of the block 15 and connected with the opening 16. A funnel or sample receiving member 20 may be connected to the block 15, by suitable means such as bolts 21, in axial alignment with the sample opening 19 for receiving a predetermined quantity of material to be sampled.

A rotary valve member 22 is provided in the block member 15. The valve member 22 has a main body portion 23 which is received in the opening 16, and a reduced body portion 24 which has a bearing 25 pressed thereon and is received in the opening 17. In addition, the valve member 22 has a hub portion 26 connected to the body portion 24 and the hub portion extends outwardly from the block member 15. The main body portion 23 of the valve member 22 and the opening 16 in the block member 15 are provided with finishes and a close tolerance so that when the valve member 22 is moved, there is no binding of the parts and yet there is no loss of material therebetween. A retaining plate 15A is provided on the end of the block member 15 after the valve member 22 has been put into place to insure that the valve member 22 is maintained in proper position. The retaining plate 15A may be secured in place by suitable means such as set screws 15B. A centrally located passage or chamber 27 is provided through the main body portion 23 of the valve member 22. The rotary valve member 22 is movable such that the passage 27 therein may either be in alignment with the sample receiving opening 19 or may be rotated to a position in alignment with the opening 18 in the block 15. As previously mentioned, the tolerance maintained between the rotary valve 22 and the opening 16 of the block or housing 15 is such that fine grains of material or portions of the sample

being tested will not be lost as the valve is rotated to position the passage or chamber 27 between the sample passage 19 and the opening 18.

The hub member 26 of the valve member 22 which extends outwardly from the block member 15 is provided with a sleeve member 28 secured thereto by suitable means, such as set screws (not shown). The sleeve member 28 has connected thereto a hand lever 29 by suitable means such as a pin 30. The hand lever 29 is effective for controlling the movement of the valve unit 22 and as specifically shown in FIG. 5, may be secured or locked into place in the grooved member 31 connected to the base 11. In addition, a spring member 32 is connected to the hand lever 29 and the sleeve member 28 and is effective for biasing the hand lever into the grooved block member 31 to insure proper location of the hand lever 29 and valve member 22.

The mechanism or jig for holding the sample cartridge 2 while it is being loaded, indicated generally at 33, is provided adjacent to the sample supply means 14. The cartridge holding member 33 includes a base portion 34 connected to the base member 11 by suitable means such as screws 35. The base member 34 is provided with a recessed opening 36, adjacent to the sample supply means 14, having a preselected shape to conform with one-half of the configuration of the capsule unit 2. The opening 36 is aligned such that when a capsule 2 is placed therein, the opening of the capsule or cavity 8 will be substantially aligned with the opening 18 of the sample supply means 14.

The opposite end of the base member 34 is provided with recesses or slots 37 for receiving the bifurcated end 38 a mating or clamping block member 39. The clamping block member 39 is connected to the base member 34 by means of pin 40 such that the block 39 may be pivoted about said pin. The block member 39 is provided with an opening 41 which conforms to the other half of the cartridge member 2 such that when the base member 34 and block member 39 are in mating engagement, the cavities or openings 36 and 41 define an opening having the precise configuration of the capsule 2. It should be understood that other proportions of recessed areas could be provided in each of the block members for properly positioning the cartridge 2; however, it has been found to be preferable that each of the blocks have a recessed area for accommodating approximately one-half of the cartridge. In this manner, the cartridge 2 may be properly positioned with an opening 2A provided in the jig 34 in substantial axial alignment with the opening 18 in the housing 15. Also attached to the clamping block member 39 is the bifurcated end of the fixture hand lever 42 and this connection may be made by any suitable means, such as pins 43. The hand lever 42 has a slot 44 therethrough which receives the pin 45 provided on the slide locking member 46. The slide locking member 46 is held in place on the block member 39 by means of hold-down members 47 and 48 having slots therein which permit the ready movement of the fixture lock member 46 in a horizontal direction. It should be noted that a slot 49 is provided on the sample control means 14 which receives the end of the fixture lock 46 to insure that the capsule 2 will be locked into place when the block 39 is placed in mating engagement with the base member 34.

In addition, it should be noted that a feed mechanism 50 is provided on the sample supply means 14 by suitable means such as bolts, between the push rod 13 and the opening 18 such that closure devices or lids 3 may be automatically fed to a position in alignment with the opening 18. The feed mechanism 50 essentially consists of a groove 51 which allows the closure device 3 to be sequentially fed in the predetermined alignment to the position adjacent to the opening 18 from a source of closure devices not shown.

In operation of the apparatus 10, the push rod 13 is in its extreme rightward or inoperative position when viewed from the drawings and the hand lever 29 is in its upright position connecting the passage or chamber 27 in the rotary valve 22 with the sample supply inlet 19 and funnel 20. The hand lever 42 and fixture block 39 are in the dotted position shown in FIG. 3 which enables a sample cartridge device 2 to be placed into the opening 36 of the base member 34. With the apparatus 10 in this position a capsule 2 is then placed into the cavity 36 and the fixture block 39 moved to its position in mating engagement with the base member 34. The hand lever 42 is then pulled forward to move the fixture locking member 46 into its locking position with the end thereof in the groove 49. The capsule 2 is then locked into a position such that the cavity 8 thereof is alignment with the opening 18 of the sample feed mechanism 14. A predetermined amount or quantity of the material to be sampled is then supplied through the funnel 20 and sample supply 19 into the passage or chamber 27 of the rotary valve 22. Once the sample material has completely passed into the chamber 27, the hand lever 29 is moved to its position connecting the chamber 27 with the passage 18 of the sample feed means by placing the hand lever 22 in the slotted groove of the block 31. The spring 32 serves to insure that the hand lever 29 and thereby the chamber 27 is not moved out of alignment during the steps of packing the sample into the capsule 2. After the chamber 27 has been moved to its position in alignment with the opening 18, the air cylinder 12 is actuated serving to drive the piston and push rod 13 in its operative position towards the left as viewed in the FIGS. 3 and 4 such that the push rod 13 is effective to engage and move a closure device 3 into and through the chamber 27, thereby being effective to move the sample material contained in the chamber 27 through the passage 18 and into the cavity 8 of the capsule 2. Since the pressure which is exerted by the push rod 13 may be controlled by the air pressure supplied to the air cylinder 12, it is possible to predeterminately adjust this pressure such that the material and closure device supplied to the capsule 2 will only be inserted with enough pressure to insured that the flange member 7 passes the lip means 5 and that the gripping engagement is effective between groove 6 and said lip. The closure device 3 is then fitted in place in the capsule 2 and the sample material contained in the cavity 8 substantially fills said cavity without the occurrence of voids or air spaces due to over-compression of the material as the lid is applied thereto. The air cylinder is then actuated such that the push rod 13 is moved to its rightward end or inoperative position and the hand lever 29 may be returned to its original starting position. The capsule device 2 may then be removed from the fixture opening and further processed as desired.

It should be noted that if desired, the apparatus 10 may be provided with a safety circuit by providing an electrical switch in the slotted groove member 31. The switch would serve as a check on the actuation of the air cylinder 12. In this manner, only when the lever 29 was engaging the switch could the air cylinder 12 be actuated. This would prevent the air cylinder 12 from being actuated when the passage 27 was not in alignment with the opening 18.

From the foregoing, it is now apparent that a novel sample capsule and apparatus for packing same has been disclosed meeting the objects and advantages set out hereinbefore and that minor modifications or changes could be made without departing from the spirit of the invention.

I claim:

1. Apparatus for automatically packing a material and closure means into a cartridge which grippingly engages the closure means comprising a base, valve means on said base including a chamber for receiving the material, said valve means being movable in response to an applied force from a first position for receiving the material from a supply into said chamber to a second position preventing further supply of material to said chamber and permitting the flow of material from said chamber to said cartridge, a jig member on said base adjacent one side of said valve means and having a recessed portion substantially conforming to the shape of said cartridge, said recessed portion being adapted to receive and hold said cartridge therein during the filling and closure of said cartridge, an opening in said jig member connecting said recessed portion with said chamber when said valve means is in the second position, packing means on said base movable between an inoperative position and an operative position, other means on said base between said packing means and said valve means controlling the supply of closure means to a position in alignment with said chamber when said valve means is in the second position to permit the flow of material to said cartridge, said packing means being responsive to an applied force to move toward its operative position engaging said closure means and urging said closure means and the material from said chamber into the cartridge until said closure means is grippingly engaged by said cartridge.

2. The apparatus according to claim 1 wherein said jig member comprises a cartridge holding member and a clamping member pivotally connected to said holding member, said recessed portion being defined by a first recessed portion in said holding member having a shape substantially conforming to the shape of a portion of said cartridge and a second recessed portion in said clamping member having a shape conforming to the shape of the remaining portion of said cartridge and aperture means in said holding member and said clamping member connecting said recessed portions with said chamber when said valve is in the second position to permit the flow of material to said cartridge.

3. The apparatus according to claim 1 wherein said valve means comprises a housing, an enlarged opening in said housing and an axially aligned opening through said housing and connecting with said enlarged opening, a valve member movable in said enlarged opening and in sealing engagement with said housing, said valve

member having a passage therethrough to define said chamber, said valve member and chamber being movable from the first position receiving the material into the chamber to the second position wherein said chamber is aligned with said axially aligned opening, a hub portion on said valve member extending through said housing and a lever connected to said hub portion

for moving said valve member between the first position and the second position and locking means on said base for releasable gripping engagement with said lever to secure said valve member in the second position and aligned with said axially aligned opening.
